UNITED STATES PATENT OFFICE.

HARRY HARDWICK, OF PHILADELPHIA, PENNSYLVANIA.

JACQUARD MECHANISM FOR LOOMS.

SPECIFICATION forming part of Letters Patent No. 592,005, dated October 19, 1897.

Application filed January 21, 1897. Serial No. 620,028. (No model.)

To all whom it may concern:

Be it known that I, HARRY HARDWICK, a citizen of the United States, residing at Philadelphia, county of Philadelphia, and State of Pennsylvania, have invented a new and useful Improvement in Jacquard Mechanism for Looms, of which the following is a full, clear, and exact description, reference being had to the accompanying drawings, which form a part of this specification.

My invention relates particularly to certain improvements appertaining to the lifting-cord and lingo band or cord of the harness of a loom in conjunction with the lifting-board.

15 The particular object I attain is to keep the warp and harness in proper position and relieve or modify the wear on the lifting cord or harness. Speaking generally, so far as the lifting-cord is concerned, I attain this object by using a supplemental board beneath the lifting-board and to which lifting-board the supplemental board is connected, so that the two move together. The cord passes through an orifice in this supplemental board and has 20 connected with it, beneath the supplemental board, a spring, one end connected with the cord, the free end resting against the supplemental board. So far as the lingo band is concerned, I remove the lingos or weights 25 now used and substitute a spring, one end of which is attached to the lingo band, the other end either free and resting against a frame connected to and moving with the journal, or is connected to a frame moving with the 30 journal.

I will first describe the embodiment of my invention illustrated in the accompanying drawings and then particularly point out the invention in the claims.

40 In the drawings, Figure 1 is a perspective view of part of the harness of a loom. Fig. 2 is a similar view in section. Fig. 3 is a detail view of a modified arrangement of spring.

A is the top board; B, the lifter-board, having the orifices b, as in the ordinary jacquard of that type.

45 C are the needles; D, the lifting-cords, which are connected at their lower ends to the leashes d, each leash passing through an orifice in the journals K², and is connected with a mail E, through the eye e of which the warp passes. A knot k on the leashes above the

journals causes the leash below the journal, with its mail and warp, to be moved when the corresponding journal is elevated. The cord 55 D is fixedly connected at the upper end to the top board A, and passes through the orifice b in the lifter-board B, and through orifices in the fixed guide-boards F and G.

Between the guide-boards F and G and connected by means of links b' with the lifter-board B is the supplemental board H, through an orifice in which the cord D passes.

50 I are springs corresponding in number to the cords D, and each cord has a spring one 65 end of which is connected to the cord, the other free and resting against the board H. As shown, these springs I are spiral springs and surround the cords.

The weight of the board puts sufficient pressure upon the spring to cause it to exercise sufficient tension on the cord to enable the cord to be held properly to be acted on by the needles and the lifting-board, the action of the needles being to bring the knot d' on the 75 cord either in line with the circular portion or said saw-cut portion of orifice b. The lifter-board lifts those cords whose knots are in line with said saw-cut portion of orifice and pass beyond those whose knots are in line 80 with the circular portion.

The board H lifting with the lifter-board prevents too great an extent of tension being put upon the cords which lift. By this arrangement the proper tension can be put 85 upon the lifting-cords without causing the wear due to chafing and other causes where weights are used.

90 J are the lingo bands, connected with the mails E. Ordinarily lingoes or weights are connected to these lingo bands. In place of these I provide frames K K', secured to and moving with the journal K². Through orifices in the frames K K' pass the lingo bands J.

95 L are springs, one for each lingo band, which surround the lingo band and have one end connected to the lingo band, the other resting against the frame K' (see Fig. 1) or attached to the frame K. (See Fig. 3.)

100 In either case where the leash corresponding to any of the lingo bands is lifted by the lifting-board the lifting-band is lifted, and when this occurs a proper tension is maintained upon it, causing the proper tension to

be maintained on its corresponding warp. When the lingo band is down, the proper tension is kept on the warp.

Having now fully described my invention, 5 what I claim, and desire to secure by Letters Patent, is—

1. In a Jacquard mechanism, in combination, with the lifter-board and the lifting-cords, of a supplemental board connected to 10 and moving with the lifter-board provided with orifices through which the lifting-cords pass, springs connected with the lifting-cords and rendered active by said supplemental board.
- 15 2. In a Jacquard mechanism, in combination with the lifter-board and the lifting-cord, of a spring connected with the lifting-cord, and a device connected to and moving with the lifter-board adapted to render said spring 20 active.
- 25 3. In combination with the lifting-cord of a Jacquard mechanism and connection therewith with the warp, of a lingo band connected with the warp, a journal for operating the warp, frames as K, K', secured to and mov-

ing with the journals, there being orifices in said frames through which the lingo bands pass, springs equal in number to the lingo bands and interposed between said frames K, K'.

4. In combination with the lifter-board and the lifting-cords of a Jacquard mechanism, of connection between the cords and the warp, a supplemental board connected to and moving with the lifting-board provided with orifices through which the lifting-cords pass, springs connected with the lifting-cords and rendered active by said supplemental board, a lingo band connected with the warp, a spring one end connected with the lingo band, and 35 means to render said spring active and maintain it active during the movement of the warp by the lifting-cord.

In testimony of which invention I have hereunto set my hand.

HARRY HARDWICK.
